UNITED STATES PATENT OFFICE.

LESTER E. DILLON, OF JEFFERSON, SOUTH DAKOTA.

DESIGN FOR A TIRE TREAD.

Application filed November 18, 1924. Serial No. 11,397. Term of patent 14 years.

To all whom it may concern:

Be it known that I, LESTER E. DILLON, a citizen of the United States, residing at Jefferson, in the county of Union and State of South Dakota, have invented a new, original, and ornamental Design for a Tire Tread, of which the following is a specification, reference being had to the accompanying drawing, forming part thereof.

The figure shows a perspective view of

a tire embodying my design.

I claim:

The ornamental design for a tire tread, as shown.

LESTER E. DILLON
